UNITED STATES PATENT OFFICE

135,001

DESIGN FOR A VACUUM CLEANER CASING

Malcolm S. Park, Mount Kisco, N. Y., assignor to
The Singer Manufacturing Company, Elizabeth,
N. J., a corporation of New Jersey

Application December 8, 1942, Serial No. 108,981

Term of patent 14 years

To all whom it may concern:

Be it known that I, Malcolm S. Park, a citizen of the United States, residing at Mount Kisco, in the county of Westchester and State of New York, have invented a new, original, and ornamental Design for a Vacuum Cleaner Casing, of which the following is a specification, reference being had to the accompanying drawing, forming a part thereof.

Fig. 1 is a front perspective view of a vacuum cleaner casing showing my new design.

Fig. 2 is a rear perspective view of the vacuum cleaner casing shown in Fig. 1.

I claim:

The ornamental design for a vacuum cleaner casing, as shown.

MALCOLM S. PARK.
